CLAIM

The ornamental design for a display screen or portion thereof with graphical user interface, as shown and described.

DESCRIPTION

The patent or application file contains at least one drawing executed in color. Copies of this patent or patent application publication with color drawing(s) will be provided by the Office upon request and payment of the necessary fee.

The sole FIGURE shows a display screen or portion thereof with graphical user interface showing our new design.

The peripheral dashed broken lines depict a display screen or portion thereof, and form no part of the darned design. The dashed broken lines inside of the peripheral dashed broken lines form no part of the claimed design. The dashed broken line rectangles and the faded portions within depict album artwork portions of the graphical user interface which

form no part of the claimed design. The portions within the dashed broken line circles depict portions of the graphical user interface which form part of the claimed design.
